UNITED STATES PATENT OFFICE.

WILLIAM S. FOSTER, OF UTICA, NEW YORK, ASSIGNOR TO FOSTER BROS.
MFG. CO., OF UTICA, NEW YORK.

CRIB-BED.

SPECIFICATION forming part of Letters Patent No. 766,236, dated August 2, 1904.

Application filed May 9, 1903. Serial No. 156,324. (No model.)

To all whom it may concern:

Be it known that I, WILLIAM S. FOSTER, of Utica, in the county of Oneida and State of New York, have invented certain new and useful Improvements in Crib-Beds; and I do hereby declare that the following is a full, clear, and exact description of the invention, which will enable others skilled in the art to which it appertains to make and use the same, reference being had to the accompanying drawings, and to the numerals of reference marked thereon, which form part of this specification.

The object of my invention is to provide a child's crib or bed having vertically-movable sides, which are mounted so as to be well supported and yet freely movable.

A further object is to provide a construction of crib which permits the application of vertically-movable sides.

In the drawings, Figure 1 shows a perspective view of a crib embodying the features of my invention, with one of the sides in its upper position and one in its lower or open position. Fig. 2 is an enlarged detail showing one of the posts employed in the construction, together with the slide on which the crib side is mounted. Fig. 3 is a detail showing the mounting of the upper end of the slide or guide-rod, in connection with a pivoted catch or hook for securing the side in its upper position. Fig. 4 shows a plan view of the parts shown in Fig. 3. Figs. 5 and 6 show side and edge views, respectively, of said hook or catch. Fig. 7 shows details of the middle support of the guide-rod for the movable sides. Fig. 8 shows a plan view of the same. Fig. 9 shows a plan view, and Fig. 10 a side elevation, of the lower bracket or support for the guide-rod. Fig. 11 shows, partially in plan view and partially in section, details of the corner-fastener employed in the construction. Fig. 12 shows a plan view of the post part of the said corner-fastener.

Referring to the reference-figures in a more particular description, 1 indicates the head-frame and 2 the foot-frame of the crib, each of which includes the corner-posts 3. On the post 3 there are provided the inwardly-projecting post-pieces 4, which carry

on their projecting ends the button-head projection 5. The bed or mattress bottom 6 is provided with a frame consisting of end bars 7 and side rails 8. To the frame is attached the rail or frame member of the corner-fastener 9, having shoulders adapted to engage with said headed projection 5. By employing the inwardly-projecting or offset corner-fasteners 4 on the post the side rails 8 of the mattress-frame may be brought inside of the track-line between the posts of the head and foot frames. The crib is provided on either side with vertically-sliding sides 10 in the nature of gates. For supporting these sides at either end there are provided vertical guide-rods 11. The guide-rods 11 are mounted at each end in brackets 12 and 13 at the upper and lower ends of the posts, respectively and projecting from the post toward the opposite end of the bed. There is also provided for the guide-rod 11 a middle support 14 in the nature of a bracket secured to and projecting over the side of the post 3. The bracket or support 14 is provided with an elongated opening 14^a therein, through which the rod 11 passes and which allows a considerable freedom of movement lengthwise of the bed-bottom, but secures the rod against lateral or transverse movement. The sides 10 engage the rod 11 by means of eyes 10^a 10^b, The upper one of these engages on that portion of the rod 11 which is between the top bracket 12 and the middle support 14, while the lower eye engages between the middle support 14 and the lower bracket 13. For supporting the sides in their upper or closed position there are provided gravity hooks or catches 15. These are pivoted on the ends of the brackets 12 and are provided with a counterweight 15^a, adapted to throw them into closed position, which is a substantially vertical position. In order to limit the swinging movement of the catches 15, there is provided on the catch a shoulder 15^b, adapted to engage on a suitable shoulder on the end of the bracket 12. When the crib side is raised to its elevated position, it is caught and held by the automatic operation of the catches 15. It is in the upper position that the sides 10

are more particularly in use, or in position to perform the office for which they are intended. In their upper position they are particularly subject to the strain of being forced outwardly, particularly at their outer side. In order to withstand this strain effectually, the middle support 14 for the rod 11 becomes quite necessary. In the manufacture of beds and cribs in practice the work is quite roughly and inaccurately formed, and the posts at opposite ends, too, are quite prone to not be exactly parallel. In employing a vertically-sliding side sufficient form must be allowed in the eyes 10^a and 10^b on the ends of the sides to obviate as far as possible any tendency to point. In addition to this it is found necessary to provide in the support 14 the elongated opening 14^a shown, which will allow a certain amount of spring to the rod 11 in a direction lengthwise of the bed. By allowing the rod to spring thus in the middle the tendency to pinch and point the sides and prevent their free vertical self-movement is to a large extent obviated, while the support against lateral pressure is maintained.

To lower the sides of the crib, the catches 15 are released, when the crib side will drop down or can be forced down into its lower

position. The arrangement of parts is preferably such that in its lower position the upper edge of the crib side will project somewhat above the plane of the bed-bottom 6, serving to prevent displacement of any mattress or bedding on the bed-bottom.

What I claim as new, and desire to secure by Letters Patent, is—

The combination in a crib-bed of a mattress-frame and head and foot frames including posts at the corners attached to said mattress-frame, of vertical guide-rods extending parallel with the posts above and below the plane of the mattress-frame, supporting brackets from the post for the upper and lower ends and middle of said guide-rods, a gravity-catch pivoted on the said upper bracket, vertically-sliding sides having bearings on said guide-rods between the upper and middle bracket and the middle and lower brackets, substantially as set forth.

In witness whereof I have affixed my signature, in presence of two witnesses, this 30th day of April, 1903.

WILLIAM S. FOSTER.
